UNITED STATES PATENT OFFICE.

WILLIAM C. PERKINS, OF ROCKY HILL STATION, KENTUCKY.

CAR-COUPING.

SPECIFICATION forming part of Letters Patent No. 602,359, dated April 12, 1898.

Application filed December 21, 1896. Serial No. 616,477. (No model.)

To all whom it may concern:

Be it known that I, WILLIAM C. PERKINS, a citizen of the United States, and a resident of Rocky Hill Station, in the county of Edmonson and State of Kentucky, have invented 5 certain new and useful Improvements in Car-Couplings, of which the following is a specification.

My invention relates to an improvement in 10 link-and-pin car-couplers; and the invention pertains more especially to the means for mechanically and automatically operating the coupling-pin to raise and lower the same in uncoupling and coupling cars, respectively.

15 The invention consists in the parts shown in the drawings, described in the specification, and more particularly pointed out in the claim.

20 In the accompanying drawings, which illustrate my invention, Figure 1 is a longitudinal section through two connecting draw-heads and couplings, with the adjacent parts of the cars and the pin-lifting device in elevation; Fig. 2, a front elevation of one of the draw- 25 heads and of the adjacent parts of a car and the pin-lifting device; Fig. 3, a side elevation of my improved coupling and the adjacent parts of a car, and Fig. 4 a plan view of said coupling and adjacent parts of a car.

30 The draw-head A is made in two sections A' A², divided horizontally in the line of the draw-bar and links, said sections being securely held together by bolts a, which pass vertically through the sections at the sides 35 thereof, and the two sections forming the draw-head are held up against the under side of the frame of the car by means of wrought-iron or steel straps B, which allow the couplings head endwise movement against the 40 back pressure of coiled buffer-springs C, encircling the draw-bar D and held between a transverse frame-piece of the car (not shown) and the end of the draw-head.

45 The end of the draw-head is recessed at a' and provided with a horizontal link-recess a², extending diametrically and centrally from the recess a' to a point beyond a coupling-pin hole a³, which passes vertically through the draw-head from top to bottom thereof and has 50 an enlargement a⁴ at its upper end to receive the head e of a coupling-pin E, the bottom of

said enlargement a⁴ providing a seat for the coupling-pin when it is dropped down to engage with the link F when the latter has been pushed into the recess a², and thus secure the 55 free end of the link to the draw-head. A cap e', having a small chain-hole therein, prevents the pin from being pulled out or stolen, and a chain g, passing through said plate, is secured at one end to a ring in the end of the 60 coupling-pin and at the other end to a lever G, secured to a rock-shaft H, supported in bearings h transversely to the end of the car, and the ends of the rock-shaft H are provided with crank-levers H', by which means the said 65 shaft and lever G, attached thereto, may be operated to lift the chain and coupling-pin when the couplings are to be placed in position to be automatically coupled. A rod H² extends from the lever G to the top of the car, 70 and the said lever and coupling-pin connected therewith may thus be operated from the top of the car when required.

The draw-head has a central longitudinal aperture a⁵ therein, communicating with the 75 link-recess a² at its juncture with the coupling-pin hole a³, which receives the forward reduced portion k' of a propeller-block K, the rear and enlarged end k² of which moves freely in an enlarged extension-aperture a⁶ of the central 80 longitudinal aperture a⁵, and a bearing-plate a⁷, secured within the said extension-aperture a⁶, carries a guide-pin k³, projecting rearwardly from the propeller-block K, and also serves as an abutment for the end of a coiled 85 spring k⁴, which encircles the guide-pin k³ and bears at its forward end against the enlarged end k² of the propeller-block K and holds the latter normally pressed to the forward end of its recess. The forward end k' 90 of the propeller-block is recessed upon the under side at k⁵ to receive the end of the link F and hold the latter in a horizontal position to connect with the car to be coupled. The lip k⁶ thus formed above the recess k⁵ when 95 the link is withdrawn from the draw-head will project across the coupling-pin hole a³ and hold the coupling-pin up until the link again pushes back the propeller-block and allows the pin to fall therein.

100 The coupling-pin may be easily operated from either side or from the top of the car, as

may be desired, and the said pin will fall automatically when the link is pushed into the draw-head as the cars come together.

The draw-head is made in a simple, strong, 5 and effective manner and will hold together under all conditions to which it may be subjected.

I claim as my invention and desire to secure by Letters Patent—

10 A car-coupling comprising a draw-head of two sections divided horizontally and longitudinally, a groove in the meeting sides of each section, a plate secured to the upper section having a depending flange extending 15 into the recess formed by the sections, a pro-

peller-block located in the recess having a stem projecting through the depending flange, a spring encircling the stem and interposed between the flanges and the propeller-block, a vertical orifice in the draw-head, and a pin ²⁰ housed in the orifice, substantially as described.

In testimony that I claim the foregoing as my invention I have signed my name in the presence of two subscribing witnesses.

WILLIAM C. PERKINS.
